(57) **CLAIM**

The ornamental design for the metal vertical back dining set, as shown and described.

DESCRIPTION

FIG. 1 is a front, bottom perspective view of the metal vertical back dining set in the combined state, showing my new design;

FIG. 2 is a front, left, top perspective view of the first piece of metal vertical back dining set, showing my new design;

FIG. 3 is a rear, right, bottom perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is a front, left, top perspective view of the second piece of metal vertical back dining set, showing my new design;

FIG. 11 is a rear, right, bottom perspective view thereof;

FIG. 12 is a front elevational view thereof;

FIG. 13 is a rear elevational view thereof;

FIG. 14 is a left side view thereof;

FIG. 15 is a right side view thereof;

FIG. 16 is a top plan view thereof;

FIG. 17 is a bottom plan view thereof;

FIG. 18 is a front, top perspective view of the third piece of metal vertical back dining set, showing my new design;

FIG. 19 is a rear, bottom perspective view thereof;

FIG. 20 is a front elevational view thereof;

FIG. 21 is a rear elevational view thereof;

FIG. 22 is a left side view thereof;

FIG. 23 is a right side view thereof;

FIG. 24 is a top plan view thereof;

FIG. 25 is a bottom plan view thereof;

FIG. 26 is an enlarged view of detail 26 in FIG. 6;

FIG. 27 is an enlarged view of detail 27 in FIG. 12;

FIG. 28 is an enlarged view of detail 28 in FIG. 13;

FIG. 29 is an enlarged view of detail 29 in FIG. 14;

(Continued)

FIG. 30 is an enlarged view of detail 30 in FIG. 19;
 FIG. 31 is an enlarged view of detail 31 in FIG. 19;
 FIG. 32 is an enlarged view of detail 32 in FIG. 20; and,
 FIG. 33 is an enlarged view of detail 33 in FIG. 25.
 The dash-dot-dash broken lines are for notating enlarged
 views and form no part of the claimed design.
